United States Patent Office

Des. 186,344
Patented Oct. 13, 1959

186,344

PENCIL SHARPENER

Jack Fairchild Fleming, Summit, N.J., assignor to Sterling Plastics Co., Union, N.J., a corporation of New Jersey

Application February 11, 1959, Serial No. 54,553

Term of patent 14 years

(Cl. D74—21)

FIG. 1

FIG. 2

Fig. 1 is a top perspective view of a pencil sharpener embodying my new design; and

Fig. 2 is a bottom perspective view thereof.

The drawing has been stipled in parts to indicate color contrast.

I claim:

The ornamental design for a pencil sharpener, substantially as shown and described.
